UNITED STATES PATENT OFFICE

169,955

VEHICLE

Philip O. Wright, Clawson, Mich., assignor, by
mesne assignments, to Willys Motors, Inc., To-
ledo, Ohio, a corporation of Pennsylvania

Application November 1, 1951, Serial No. 17,221

Term of patent 14 years

(Cl. D14—3)

To all whom it may concern:

Be it known that I, Philip O. Wright, a citizen of the United States, residing at Clawson, county of Oakland, and State of Michigan, have invented a new, original, and ornamental Design for a Vehicle, of which the following is a specification, reference being had to the accompanying drawings, forming part thereof.

Figure 1 is a side elevational view of a vehicle showing my new design;

Figure 2 is a front quarter perspective view of the vehicle;

Figure 3 is a rear view of the vehicle, and

Figure 4 is a rear quarter perspective view of the vehicle.

The characteristic features of my design reside in the portions shown by means of full lines in the drawings.

What I claim is:

The ornamental design for a vehicle, as shown and described.

PHILIP O. WRIGHT.
